UNITED STATES PATENT OFFICE.

CHARLES TWEEDIE, OF JEFFERSON CITY, MISSOURI.

FOOTWEAR.

Application filed July 3, 1922. Serial No. 572,538.

My invention relates to footwear and has for its principal objects to produce an article of footwear that may be worn with its upper portion in various positions. The invention consists principally in a shoe or boot top wherein the quarters meet near the throat without any substantial overlapping at this point and wherein the quarters are substantially symmetrical above the throat and have a progressively increasing lap above said throat. It also consists in the parts and combinations of parts hereinafter described and claimed.

In the accompanying drawing wherein like numerals refer to like parts wherever they occur,

Fig. 1 is a perspective view of a shoe fitted with a boot top embodying my invention, the top portion of the boot top being shown unbuttoned and flaring open;

Fig. 2 is a similar view with the upper portion of the boot top rolled down;

Fig. 3 is a similar view with the front quarters of the boot top overlapping and buttoned together; and

Fig. 4 is a side view of the boot top alone.

My present boot top comprises quarters 5 whose lower edges are cut along the front portion to conform to the lines of a circular 30 vamp shoe and along the back portion to conform to the heel seat of the shoe S, the intermediate portion of said quarters being connected together by a strap 6 that is separate or integral therewith and adapted 35 to pass under and conform to the shank of the shoe. The lower portion of the present boot top conforms more or less closely to the specification of my Patent No. 1,153,977. At or just above the throat, the quarters 40 meet, substantially without overlapping; and at this point they are held together by any suitable detachable fastener, preferably by a short strap or tab 7 that is secured to one of the quarters (preferably the inside 45 quarter) and whose free end is provided with a button hole 8 in a position to button over a button 9 provided therefor on the other quarter or on a tab secured thereto. Below this strap, the inside quarter has a fly 50 10 that overlaps the front edge of the outer quarter and is provided with button holes 11 in a position to engage buttons 12 provided therefor on the outer quarter. Above the strap 7, the front edges of the quarters overlap, 55 the overlapping increasing more and

more upwardly from the strap, and the inside quarter is provided with a button hole 13 in position to button over a button 14 provided therefor near the top of the outer quarter. Above the strap, the inner and outer quarters are substantially symmetrical; that is, the upper front portions 15 lap equal distances beyond the vertical plane passing through the front of the shoe.

In consequence of the arrangements above 60 described, my boot top may be worn in either of three positions. That is, first, it may be worn after the manner of a full length upper with the front quarters overlapping and secured together with the button 65 14; second, it may be worn with the quarters unfolded but with the top portion unbuttoned and flaring open; and third, it may be worn with the upper portions rolled down to the point fixed by the throat strap 70 75 7.

In order to enhance the attractive appearance of the article, it is preferable to line it, for at least as far down as the throat strap, with a material of contrasting color or appearance from that of the outside. 80

Preferably my boot top is made of broad-cloth or other similar fabric and obviously admits of numerous modifications without varying from my invention. For instance, it is unimportant whether the button hole 85 fly is integral with the inside quarter or whether it is made as a separate piece and stitched to said quarters. Likewise, it is unimportant whether the quarters are secured together by buttons and button holes, as 90 illustrated in my Patent No. 1,368,771 or whether they are laced together as illustrated in my Patent No. 1,265,280. Likewise, the button strap may be replaced with any suitable device for detachably securing 95 the quarters together just above the ankle, as for instance, with a metal buckle or with hook and eye or, in case of a laced boot top, the lace answers the purpose. Therefore I do not wish to be restricted to the details 100 hereinbefore described.

While I have described my invention as embodied in a boot top adapted to be worn over a low shoe, it is obviously capable of being embodied in a complete shoe and it 105 is so illustrated in the drawing.

What I claim is:

1. An article of footwear comprising an inside quarter and an outside quarter, which are secured together along the back of the 110

- article and whose front edges substantially meet at the front line of said article near the throat thereof and are provided with means passing across said throat for detachably securing said quarters together, said inside quarter having an upper fly and a lower fly which extend beyond said front line and are provided with means for detachably securing them to said outside quarter.
2. An article of footwear comprising a high inside quarter and a high outside quarter secured together along the back of said article, and means at the throat for detachably securing said quarters together and independent means near the top for detachably securing them together, the front edge of said quarters meeting close to said throat and said quarters being substantially symmetrical with relation to the front line of said article above said throat and adapted to overlap above said throat.
3. An article of footwear comprising a high inside quarter and a high outside quarter secured together along the back of said article and whose front edges substantially meet near the throat, means at the throat for detachably securing said quarters together and independent means for detachably securing them together near the top, said quarters increasing in width above said throat and being substantially symmetrical with relation to the front line of said article
- above said throat and adapted to overlap each other above said throat.
4. An article of footwear comprising a high inside quarter and a high outside quarter secured together along the back of said article and means for detachably securing said quarters together across the throat and independent means for detachably securing them together near the top, the inside quarter increasing in width above and below said throat fastening and the outside quarter being substantially symmetrical with it above said throat and said quarters being adapted to overlap each other above said throat, said article having an inside lining for its top portion which contrasts in color with the outside color of said article.
5. A boot top of the kind described comprising an inner flexible quarter and an outer flexible quarter secured together along the back of said boot top and means located just above the ankle for securing them together at the front without substantial overlapping just above the ankle, the portions of the inner quarter above and below said means overlapping the outer quarter to form securing flies and being provided with detachable fasteners.

Signed at Jefferson City, Mo., this 30th day of June, 1922.

CHARLES TWEEDIE.
